UNITED STATES PATENT OFFICE

155,008

DESIGN FOR A PERFUME BOTTLE OR THE LIKE

Leonard W. Herman, Philadelphia, Pa.

Application October 22, 1947, Serial No. 142,090

Term of patent 7 years

(Cl. D58—6)

To all whom it may concern:

Be it known that I, Leonard W. Herman, a citizen of the United States of America, residing at city of Philadelphia, county of Philadelphia, and State of Pennsylvania, have invented a new, original, and ornamental Design for Perfume Bottles or the like, of which the following is a specification, reference being had to the accompanying drawing, forming a part thereof.

Figure 1 is a rear elevation of a perfume bottle, or the like, embodying my new design;

I claim:

The ornamental design for a perfume bottle or the like, as shown.

LEONARD W. HERMAN.
